(57) **CLAIM**

The ornamental design for a toy, as shown and described.

DESCRIPTION

FIG. 1 is a rear, left and top perspective view of a toy, showing my new design;

FIG. 2 is a front, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is a perspective view in the disassembled configuration thereof; and,

FIG. 10 is an enlarged view of portion of FIG. 1 thereof. The evenly spaced broken lines are directed to portions of the article that form no part of the claimed design, and the dot-dash broken lines in the drawings depict the bounds of the enlargement that form no part of the claimed design.
